Attorney

UNITED STATES PATENT OFFICE.

ROLLAND G. WILLIAMS, OF BRIDGEPORT, CONNECTICUT.

REINFORCING CLAMP FOR JOINTED IRON POLES.

Application filed January 20, 1925. Serial No. 3,563.

This invention relates to reinforcing clamps for iron poles, the latter being formed of sections of decreasing diameters from bottom to top.

5 Iron poles of an approved form are formed of hollow sections, each successive section having a diameter less than that of the section immediately preceding.

The pole is constructed by shrinking these 10 sections within each other, and the resultant circumferential and substantially horizontal ledge at each joint has been covered with a cement that is supposed to protect the joints against erosion.

15 But it has transpired that, while this cement is usually effective, there are certain localities where it is disintegrated by the chemical action of the elements, the result being the destruction of the pole joints, 20 thereby causing great expense for replacement.

The object of this invention is to so repair a pole, injured as above noted, that its strength and utility will be fully preserved, 25 at an expense that is a mere trifle as compared with the cost of a new pole and its mounting.

In the accompanying drawing

30 Figure 1 is a side elevation showing a section of a pole with my improvement applied thereto,

Figure 2 is a cross section taken at the line 2—2 of Figure 1, and

35 Figure 3 is an illustration similar to Figure 1 from another viewpoint, one of the clamp members being shown in section.

1, 2, denote pole sections, the smaller section 1 being shrunk within the larger section 2, and leaving a circumferential ledge 3 at the joint, as shown at Figure 3. 4, 5, 40 are the members of the improved clamp, each member having two diameters, one for the pole 1 and the other for the pole 2.

45 Where the different sized parts of each member adjoin, a jog 6 is formed, which, when the members are in position around the pole sections, rests upon and closely conforms to the ledge 3.

The members 4, 5, are formed with verti-

cal side ribs 7, 8, that are intersected by 50 horizontally disposed ribs 9, 10, so that it will be clear that the members are well reinforced.

At the ends of the ribs 9, 10, are diverging portions 11, 12, within which are formed 55 recesses 13, 14, and flanges 15, 16, and 17, 18, extend from the ends of the clamping members and form side walls of the recess. The members are secured in position by bolts 19 driven through the flanges and drawn tight 60 by the usual nuts 20, the inner faces of these members being curved throughout their lengths to closely contact the pole sections, while the weight of the upper pole section, 65 which might cause it to telescope within the lower section, is sustained not only by the clamping members but by the ledge 3, or, in other words, by the upper end of the lower pole section, and in this connection attention is called to the fact that the bolt heads 70 and nuts are housed within the recesses so as not to present unsightly projections.

The flanges themselves contribute to the strength of the clamping members, and when the latter are clamped firmly around a pole 75 at the joint, the pole sections will be individually held and the pole itself will be better than new since erosion can never take place at the clamped joint.

What is claimed is:—

80 A repair clamp for iron poles formed of sections of different diameters with a resultant circumferential ledge formed at the junction of said sections, comprising two elongated clamping members curved to conform 85 closely throughout their length to the pole and having two diameters corresponding to those of said sections whereby a shoulder is formed which rests upon said ledge, said members having vertical and horizontal ribs 90 and provided with flanges at their ends, and bolts and nuts for drawing these flanges together and clamping the members to the pole.

95 In testimony whereof I affix my signature hereto.

ROLLAND G. WILLIAMS.
